UNITED STATES PATENT OFFICE.

JAKOB KORDYL, OF CARNEGIE, PENNSYLVANIA.

RAIL-FASTENER.

1,372,519.

Specification of Letters Patent. Patented Mar. 22, 1921.

Application filed November 24, 1920. Serial No. 426,152.

To all whom it may concern:

Be it known that I, JAKOB KORDYL, a citizen of the United States of America, residing at Carnegie, in the county of Allegheny and State of Pennsylvania, have invented certain new and useful Improvements in Rail-Fasteners, of which the following is a specification.

This invention relates to certain new and useful improvements in rail fasteners and has for one of its objects to provide rail clamps interlockingly associated with the supporting tie for the rails.

A further object of the invention resides in the provision of a rail fastener wherein the tie for supporting a rail is provided with a transverse seat having undercut beveled walls with which rail clamps and fastening blocks are associated for holding the rail against vertical movement relative to the tie.

With the above and other objects in view, the present invention consists in the novel form, combination and arrangement of parts hereinafter more fully described and shown in the accompanying drawings, in which like reference characters refer to corresponding parts throughout the several views.

In the drawings,

Figure 1 is a side elevational view of a tie 30 constructed in accordance with the present invention, the rails seated thereon being shown in section,

Fig. 2 is a top plan view of the same,

Fig. 3 is a cross sectional view taken on line III—III of Fig. 2 showing one rail clamp 35 interlocked with the supporting tie,

Fig. 4 is a cross sectional view taken on line IV—IV of Fig. 2 showing the rail clamps interlocked to the supporting tie and a locking block for holding one of the clamps immovable,

Fig. 5 is a fragmentary top plan view of one of the ties and a portion of a rail showing the method of mounting the rail upon the tie with the rail clamps and locking blocks associated therewith,

Fig. 6 is a perspective view of one end of a tie showing the rail seat therein,

Figs 7 and 8 are detail perspective views 50 of the locking blocks for holding the rail clamps in position,

Fig. 9 is a fragmentary side elevational view of meeting rail ends, and

Fig. 10 is a cross sectional view taken on line X—X of Fig. 9 showing the tongue and 55 groove connection between the rail ends.

Referring more in detail to the accompanying drawings, there is illustrated a supporting tie 1 having rails 2 mounted thereon and retained in position by clamping members 3 and 4.

A tie 1 is constructed to provide a seat for the rail 2, the tie being transversely cut at each end thereof to provide a seat portion 5 having vertical outer end walls 6 and a vertical inner wall 7. As shown in Figs. 5 and 6, the inner wall 7 is cut away to provide a lateral seat portion 8 having undercut beveled walls 9 and 10, the wall 10 and seat 8 extending to the adjacent edge of the tie. 70 The outer wall 6 of the seat 5 is cut away intermediate the ends thereof to provide a lateral seat portion 11, the walls 12 of which are undercut adjacent the seat 5 while the side walls 12' at the outer end of the seat 11 extend vertically, the transverse end wall 13 of the seat 11 being undercut as shown in Figs. 1 and 4. A screw bolt receiving opening 14 is provided in the seat portion 8 while a similar opening 15 is formed in the 80 seat portion 11.

The base flanges of the rail 2 are directly received on the seat 5 as shown in Fig. 4 with the opposite edges thereof engaging the side walls 6 and 7 of the seat, the rail clamp 4 comprising the body portion 16 carrying a depending block 17 with the opposite sides and outer edge having a transverse groove therein defining projections 18 to be received beneath the undercut walls 9 and 10 90 of the seat 8 and an overhanging ledge 18' to rest upon the surface of the tie 1. The inner wall of the extension block 17 is formed perpendicular as at 19 for engagement with the adjacent edge of the base flange of the rail 2. An angle extension is carried by the rail clamp 16 and includes a flange engaging portion 20 and a web engaging portion 21 for the rail. The clamping member 4 is moved laterally of the tie as shown in Fig. 5 100 during the positioning of the same and to hold the clamp 4 in such position at the inner end of the lateral seat 8, the fastening block 22 is provided, the same including an outer beveled wall 23 with the inner side thereof 105 reversely beveled as at 24, the beveled wall

23 extending beneath the beveled wall 10 of the tie while the beveled wall 24 of the block 22 overlies the adjacent side extension 18 of the clamping block 4. When in this position, a fastening bolt 25 passes through the opening 26 in the block 22 and is threaded into the opening 14 in the tie, thereby holding the clamp 4 in its correct position.

10 The clamping block 3 is of similar construction to the clamping block 4 and in mounting the clamp 3 within the seat 11, the extension portion 17 of the clamp is received in the outer end of the lateral seat 11 and moved inwardly of said seat to cause the lateral extensions 18 thereof to be received beneath the undercut beveled side walls 12 with the clamp engaging over its entire inner face the rail 2. To retain the clamp 3 in this position, the block 27 shown in Fig. 20 7 is provided, the same including vertical side walls 28 and oppositely beveled end walls 29. One beveled end wall 29 extends beneath the undercut end wall 13 of the seat 11 with the opposite beveled end wall 29 25 overlying the beveled portion 18 of the clamp 3 as shown in Fig. 4, the block 27 being provided with a central opening 30 registering with the threaded opening 15 and into which openings a fastening bolt 25 30 is received. With this construction, it will be readily seen that the rail clamps 3 and 4 are securely retained in position by the clamping blocks 22 and 27, the clamps 3 and 4 being interlocked with the tie 1 while 35 the bolts 25 retain the blocks 22 and 27 immovable with respect to the tie and clamps and also retaining the clamps immovable.

40 The connection between adjacent rail ends is shown in Figs. 9 and 10, one rail carrying a tongue 31 received in a groove 32 in the adjacent rail end, thereby insuring the meeting rail ends against relative movement.

45 While there is herein shown and described the preferred embodiment of the invention, it is nevertheless to be understood that minor changes may be made therein without

departing from the spirit and scope of the invention as claimed.

What is claimed as new is:

1. A rail tie and fastener comprising a tie 50 having cross seats, the inner end of each seat extending longitudinally of the tie being cut away and opening at one side of the tie, the outer end of each longitudinal seat being beveled, a rail positioned in the transverse seat, rail clamps interlockingly mounted in the longitudinal seats and having beveled outer ends with the outwardly positioned clamps spaced from the outer ends of the longitudinal seats, retaining blocks 60 for the clamps mounted in the outer ends of the longitudinal seat, retaining blocks for the open sides of the seat extensions and means for holding the retaining blocks fixed to the tie with the rail clamps immovable 65 relative thereto.

2. A rail tie and fastener comprising a tie having cross seats, the inner end of each seat extending longitudinally of the tie being cut away and opening at one side of the tie with the outer ends of the longitudinal seats spaced from the sides and adjacent ends of the tie, the outer end of each longitudinal seat being beveled, a rail positioned in the transverse seat, a rail clamp 75 interlockingly mounted in the outer end of each longitudinal seat with a beveled lower end wall spaced from the longitudinal seat end, a retaining block having beveled ends received in the outer end of each longitudinal seat extending into the beveled end wall of the seat with the inner end thereof overlying the beveled end of the rail clamp, a rail clamp interlockingly received in the inner end of each longitudinal seat, a retaining block positioned in the side opening of the inner end of said seat and means for securing the retaining blocks immovable relative to the tie with the rail clamps retained in position.

In testimony whereof I affix my signature.

JAKOB KORDYL.
